UNITED STATES PATENT OFFICE.

JOHN B. MORROW AND CLAUS P. GERITZ, OF BROOKLYN, NEW YORK.

SAFETY WINDOW CLEANING DEVICE AND VENTILATOR.

1,133,306.

Specification of Letters Patent. Patented Mar. 30, 1915.

Application filed January 2, 1914. Serial No. 810,041.

To all whom it may concern:

Be it known that we, JOHN B. MORROW and CLAUS P. GERITZ, citizens of the United States, residing at Brooklyn, in the county of Kings and State of New York, have invented a new and useful Safety Window Cleaning Device and Ventilator, of which the following is a specification.

The device forming the subject matter of 10 this application is a window, the same being so constructed that the upper and lower sashes thereof may readily be swung inwardly, for cleaning, thereby rendering it unnecessary for a person to climb outside of 15 the building, in order to clean the sashes.

Another object of the invention is to provide a window which will afford adequate ventilation.

It is within the scope of the invention to 20 improve generally and to enhance the utility of, devices of that type to which the present invention appertains.

With the above and other objects in view which will appear as the description proceeds, the invention resides in the combination and arrangement of parts and in the details of construction hereinafter described and claimed, it being understood that changes in the precise embodiment of the 30 invention herein disclosed can be made within the scope of what is claimed without departing from the spirit of the invention.

In the accompanying drawings:—Figure 1 shows the invention in perspective; Fig. 2 is a vertical longitudinal section; Fig. 3 is a perspective of the locking stud; Fig. 4 is a sectional detail of the lock; Fig. 5 is a top plan view of the lock; Fig. 6 is a fragmental section of one weight; Fig. 7 is a fragmental section of the hinge which connects the guide frame with the casing; Fig. 8 is a perspective of the hinge which connects the guide frame with the casing; Fig. 9 is a fragmental perspective of the upper 45 sash.

In carrying out the invention there is provided a casing 1, to the sides of which are attached fixed primary guide strips 2 co-extensive in length with the casing 1. Located parallel to the primary guide strips 2 are secondary guide strips 3. The secondary guide strips 3 terminate intermediate the upper and lower ends of the casing 1, and the lower ends of the secondary guide strips 3 are beveled as indicated at 4.

Mounted to slide between the fixed pri-

mary guide strip 2 upon the one hand and the secondary, fixed guide strips 3 upon the other hand is an upper sash 5. The upper sash 5 is supported for vertical adjustment by means of flexible elements 6. At one end, each flexible element 6 is secured as shown at 7 to the casing 1, the flexible elements passing thence around sheaves 8 secured to weights 9, the flexible element 6 being carried upwardly around sheaves 10 which are mounted on the casing 1. The lower inner ends of the flexible elements 6 are attached to the upper sash 5, as shown most clearly in Fig. 9, and as indicated at 11. 65 70

The invention further includes a movable guide frame 12, pivotally connected at its lower end with the casing 1. Any suitable means may be provided for pivotally connecting the guide frame 12 with the casing 1. As shown in Figs. 8 and 7, a pair of plates 14 are provided at each side of the movable guide frame, the plates 14 being loosely united by a headed pivot element 15. A spring washer 16 is interposed between 80 the head of the pivot element 15 and one plate 14, for the purpose of taking up wear. One of the plates 14 of each hinge is secured to the casing 1 and the other plate of each hinge is secured to the side portion of the frame 12. The upper ends of the frame 12 are beveled as shown at 17, so as to cooperate with the beveled ends 4 of the secondary guide strips 3 when the frame 12 is swung upwardly from the inclined position 90 shown in Fig. 1 into a position in alinement with the casing 1. The inner edges of the side portions of the movable guide frame 12 are provided with grooves 18 adapted to aline with grooves 19 in the fixed secondary 95 guides 3. A lower sash 20 is mounted to slide in the grooves 18 of the movable frame 12 and when the frame 12 is alined with the casing 1, the lower sash 20 may be pushed upwardly into the grooves 19 of the guides 3. 100

Flexible elements 21 are attached to the lower sash 20, the flexible elements 21 passing over sheaves 22 carried by the casing 1. Secured to the lower ends of the flexible elements 21 are weights 23. The flexible elements 21 and 6 move adjacent guide pins 24 which are inserted into the outer surface of the casing 1.

A locking means is provided for holding the guide frame 12 in alinement with the 110 casing 1 when the guide frame is swung upwardly from the position shown in Fig. 1.

With this end in view, plates 25, one of which is shown in Fig. 3, are secured to the outer side faces of the guide frame 12, the plates 25 carrying headed studs 26. Locking mechanisms are attached to the inner edges of the casing 1. Each locking mechanism comprises an outer or face plate 27 and an inner plate 28, as will be understood from Figs. 3 and 4, the plates 27 and 28 being connected by a central securing element 29 and spaced apart by studs 30. One plate carries a fulcrum pin 31 upon which is pivoted a latch 32 provided with a notch 33 which clears the central securing element 29. In the edge of the latch 32 there is a notch 34 coöperating with a notch 35 formed in the periphery of the face plate 27. At its outer end, the latch 32 terminates in a finger piece 36. A spring 37 is connected with the inner end of the latch 32 and is restrained by a stud 38. The function of the spring 37 is to maintain the latch 32 in the position shown in Fig. 4. The finger piece 36 of each latch lever projects outwardly through a notch 39 formed in the casing 1. Guide fingers 40 are secured to the edges of the movable frame 12. The function of these guide fingers 40 and their relation to the face plate 27 of the lock will be dealt with hereinafter.

Pivottally mounted upon the upper edge of the lower sash 20 is a latch 41, adapted to coöperate at different times with keepers 42 and 43, the keeper 42 being secured to the lower portion of the upper sash 5 and the keeper 43 being secured to the upper edge of the upper sash.

Presupposing that the parts are positioned as shown in Fig. 1, the guide frame 12 being lowered and being extended inwardly, it is obvious that ample ventilation will be provided for, it being possible to raise and lower the frame 12 upon its pivotal connection 14 with the casing 1, so that a draft will be prevented. When the free end of the frame 12 is swung upwardly, the flexible elements 21 and the weights 23 will exercise their obvious functions, the beveled end 17 of the frame 12 coöperating with the beveled end 4 of the fixed guide strips 3. In this manner, the grooves 18 in the guide frame 12 will be alined with the grooves 19 in the fixed guide 3, and the lower sash 20 may be moved in the usual manner. Obviously, when the frame 12 is swung upwardly, the frame coöperates with the fixed guide strips 2 to hold the upper sash 5 in place for vertical adjustment, the functions of the weights 9 being clear and readily understood. When the parts are in the positions above described, the latch 41 may be engaged with the keeper 42 on the upper

sash to lock the sashes against relative movement.

When the guide frame 12 is swung upwardly, the fingers 40 coöperate with the face plates 27 of the locking mechanism, and these face plates, therefore act as wear strips receiving the fingers 40. When the frame 12 is swung upwardly, the studs 26 on the frame will enter the notches 35 in the face plate 27 of the locking mechanism and, under the action of the springs 37, the latch levers 32 in their notched portions 34, will coöperate with the studs 26 to hold the frame 12 in alinement with the casing 1. In order to set the frame 12 free, the latches 32 may be lifted by means of the protruding finger pieces 36.

It will be clearly understood that when the frame 12 is swung downwardly into the position shown in Fig. 1, the lower sash 20 may be cleaned readily without climbing outside of the building. Should it be desired to clean the upper sash 5, the upper sash is pushed downwardly whilst the frame 12 is in alinement with the casing 1. Thereupon, the latch 41 is engaged with the keeper 43 and the frame 12 is swung inwardly and downwardly, carrying with it not only the lower sash 20 but the upper sash 5 as well. Both sashes may be carried by the frame 12 in the manner hereinbefore described, not only when it is desired to clean the sashes, but when it is desired to open the casing 1 entirely for any other purpose.

Having thus described the invention, what is claimed is:—

In a device of the class described, a casing; an upper sash mounted to slide in the casing; a frame pivoted to the casing; a lower sash mounted to slide in the frame; a locking element on the lowest sash; and locking elements upon the upper and lower ends of the upper sash, the locking elements on the upper sash being adapted to coact at different times with the locking element on the lower sash; the frame constituting means for opening the casing to permit the upper sash to be swung downwardly, along with the frame, and the lower sash and the locking element on the lower sash coöperating with the locking element upon the upper end of the upper sash, to hold the upper sash in place upon the frame.

In testimony that we claim the foregoing as our own, we have hereto affixed our signatures in the presence of two witnesses.

JOHN B. MORROW.
CLAUSS P. GERITZ.
